UNITED STATES PATENT OFFICE.

REGINALD A. FESSENDEN, OF BROOKLINE, MASSACHUSETTS, ASSIGNOR TO SUBMARINE SIGNAL COMPANY, OF PORTLAND, MAINE, A CORPORATION OF MAINE.

METHOD OF AND APPARATUS FOR OBTAINING INCREASED CIRCULATION.

1,318,740.

Specification of Letters Patent.

Patented Oct. 14, 1919.

Application filed May 25, 1918. Serial No. 236,553.

To all whom it may concern:

- Be it known that I, REGINALD A. FESSENDEN, a citizen of the United States, residing at Brookline, in the county of Norfolk and 5 State of Massachusetts, have invented new and useful Improvements in Methods of and Apparatus for Obtaining Increased Circulation, of which the following is a specification.
- 10 My invention relates to the flow or movement of bodies of one kind in a medium of a different nature and more especially to circulation in fluids, and has for its object the increasing of the efficiency and velocity of 15 such circulation.

Figures 1 and 2 show, partly diagrammatically, means for carrying out my invention.

In Fig. 1, 11 is a tank filled with a fluid to 20 the level 17. 12 is a means for producing compressional elastic waves in said fluid, consisting preferably of an oscillator of the type described in U. S. Patent 1,167,366. 13 and 14 are the leads of the oscillator and 15 is the dynamo used for excitation.

In applying the invention to impregnating wood with a preserving fluid, the wood to be impregnated, 18, is immersed in the preserving fluid in the tank 11 and the oscillator 12 being excited the compressional elastic waves generated in the fluid set up compressional elastic waves in the block 18 and increase the velocity of impregnation, 30 presumably because the vibration of the cell walls of the wood increases the rate at which the air bubbles in the wood pass outward and the rate at which the impregnating liquid flows in.

Where the invention is to be applied to 40 increasing the circulation of the human body, as for example by massage, the member to be treated, for example the arm 16, is inserted in the fluid in the tank—which in this case may be water—and on the oscillator being excited the compressional elastic waves transmitted through the water generate compressional elastic waves in the member to be treated, and such compressional elastic waves produce an increased

circulation in the member and are found to 50 produce other beneficial effects.

The application of the method to the manufacture of steel is shown in Fig. 2. Here 19 is the ingot mold filled with melted steel 20; 12 is the oscillator; 13 and 14 are 55 the oscillator leads; 15 is the dynamo driving the oscillator; and 21 is the steel bar connecting the oscillator with the ingot mold.

Where the oscillator is not used the bubbles 22 formed in the melted steel do not escape from the steel quickly enough and form what is known as a "pipe" which greatly diminishes the amount of the steel casting which is available for use, since the 60 top containing the pipe has to be cut off and remelted.

When, however, the oscillator is used, as 65 shown in Fig. 2, the compressional elastic waves cause the gas bubbles and other impurities to rise to the top before the steel gets so cool as to prevent their escape and consequently the size of the pipe is very 70 greatly reduced and may be substantially entirely absent, thereby rendering substantially 75 the entire steel casting available for use.

It has been found by experiment that 80 much better results are obtained when the oscillator is worked at certain definite frequencies. The reason for this is not definitely known but it may be possibly due to the fact that when compressional elastic waves are generated continuously resonance effects are obtained. This would appear to 85 be shown by the fact that when a block of wood is immersed, as shown in Fig. 1, at certain frequencies there is a visible intense discharge of gas or vapor from the block, which is not obtained if a single compressional wave is caused to act upon it but only 90 when a train of waves is used.

It has also been found advantageous to 95 have the frequency high, even up to 10,000 or 40,000 per second, and the wave length short. Possibly, because in this case the compressional region of the waves is closely adjacent to the expansional region and con-

sequently there is a much stronger tendency to circulatory movement, in contra-distinction to the case where the whole fluid is under compression or in expansion at the same instant or where the body of fluid is jarred as a whole.

What I claim is:

1. The method of increasing the rate of circulation of bodies of one kind immersed

in a medium of a different nature which 01
consists in generating sustained trains of
compressional elastic waves in said medium.

2. Apparatus for increasing the circulation of fluids comprising a sustained source of compressional elastic waves in operative 51
relation to said fluid.

REGINALD A. FESSENDEN.
